Max Wolkowitz, 20 Clinton St., New York, N.Y.

Filed Mar. 1, 1963, Ser. No. 73,781

Term of patent 14 years

(Cl. D21—6)

FIG. 1 is a front perspective view of a curtain showing my new design.

FIG. 2 is an enlarged detail view of a portion of the ornamentation on one of the horizontal bands extending across the curtain of FIG. 1.

FIG. 3 is a rear view of the curtain shown in FIG. 1.

FIG. 4 is a detail view, on an enlarged scale, of a portion of one of the horizontal bands extending across the curtain shown in FIG. 3;

The curtain shown in FIGS. 1 and 3 is broken away to show variable height and width.

I claim:

The ornamental design for a curtain or a similar article, as shown and described.
